PUMP

Matthew W. Huber, Watertown, N. Y., assignor
to The New York Air Brake Company, a corporation of New Jersey

Application November 5, 1945, Serial No. 626,690

4 Claims. (Cl. 103—173)

1

This invention relates to parallel cylinder pumps intended to operate at rotary speeds of 3000 R. P. M. or higher against head pressures of the order of 3500 p. s. i., and the novelty resides in means for controlling a constantly running pump by varying its displacement. The displacement control includes means to trap a bath of lubricating liquid around the working parts of the pump, in the event that the discharge line from the pump should be ruptured.

Pumps of this type are usually applied to airplane engines and in such case must run continuously. The variable volume or variable displacement control gives smooth volumetric control from zero discharge to full capacity. Pumps of this type are lubricated by the hydraulic liquid which is pumped, and many prior art pumps would be destroyed if the discharge line or parts connected thereto were ruptured, because the pump lost its lubricating liquid, or even pumped itself dry. The provision of automatic means which connects the lubricating bath to the pump circuit when the pump is operating normally and traps the lubricating bath upon loss of head pressure is consequently an important safeguard.

The volumetric control is exercised in response to head pressure by spill-back valves, one encircling each plunger externally to the cylinder, and controlling a port leading from a point within the cylinder through the plunger to a point on the plunger wholly external to the cylinder. This arrangement minimizes leakage and simplifies design and manufacture. This volumetric control arrangement in its broad aspects forms the subject matter of my application Serial No. 632,975, filed December 5, 1945, now abandoned. The present application is directed to features peculiar to multi-cylinder pumps, particularly those having the cylinders arranged in circular series, with their axes parallel.

The plungers work in a cylinder block and their outer ends are guided in guideways formed in an adjacent guide block. This guide block is so formed as to afford a chamber in which the spill-back valves and a part of the mechanism for shifting them in unison are housed.

A preferred embodiment will now be described by reference to the accompanying drawings, in which:

Fig. 1 is a longitudinal axial section of a nine cylinder pump embodying the invention.

Fig. 2 is an exploded view of the capacity adjusting motor.

Fig. 3 is a section on the line 3—3 of Fig. 1.

Fig. 4 is a view similar to a portion of Fig. 1

2

showing the spill-back valves in the zero capacity position.

Statements of direction used in the following description refer to the pump positioned as in Fig. 1.

The housing of the pump comprises a body 6 and a cap 7. The cap has an inlet connection 8 and a discharge connection 9 which take the form of tapped ports into which the suction and

10 discharge pipes (not shown) are screwed.

Clamped between a shoulder 11 in the body and a shoulder 12 in the cap is the cylinder assembly made up of a cylinder block 13 and a guide block 14. These are annular in form and enclose 15 between them a chamber 15 which communicates with the inlet port 8 by way of a passage 16 formed in the cylinder block.

The outer periphery of the cylinder block 13 is channeled to receive a ring gasket 17 which 20 seals the joint between the body 6, cap 7 and cylinder block 13. A ring gasket 18 seals the inner periphery of the cylinder block to the cap. In this way an annular discharge channel 19 formed in cap 7 is isolated. It communicates 25 with the discharge connection 9 through passage 21.

The cylinder block 13 is bored through to form the cylinders 22 and the discharge valves 23 are cup-shaped, and are seated by coil compression 30 springs 24 against the outer face of the cylinder block. They are guided in pockets bored in the cap 7, as shown.

The small spring loaded relief valve 25 leading from discharge connection 9 is so adjusted that 35 it will open at a pressure slightly lower than that which will set the capacity control for zero discharge. The relief valve discharges to the sump from which the pump draws the oil which it pumps. The function of the relief valve is to open just before the pump reaches zero capacity setting and thus assure that the pump will discharge at least a small quantity of oil so long as the discharge line is intact. The quantity of oil so circulated is the minimum necessary to cool 40 the pump when operating against the established head pressure.

The intake ports for the cylinders 22 are 45 grooves 26, one in each cylinder, each connected with inlet 8 by a passage 27 drilled in the cylinder block 13. The guide block 14 has bores aligned with the cylinders 22 and of the same diameter. Alignment is maintained by a dowel, 50 diagrammatically indicated at 28.

For each cylinder 22 there is a plunger 29 which 55 extends through a bore in block 14, across cham-

ber 15 and into its cylinder 22. The lower plunger 29 in Fig. 1 is in its fully retracted position in which its end is between the margins of groove 26. The upper plunger 29 in Fig. 1 is in the fully advanced position in which it is substantially in contact with its discharge valve 23.

The plungers are retracted by coil compression springs 31 reacting between block 14 and flanges on the outer ends of respective plungers. Each plunger carries a universally tiltable thrust head 32.

The drive shaft 33 is counterbored at 34 from its inner end, the counterbore opening into chamber 15. Keyed to shaft 33 is a swash plate 35, which actuates the plungers 29 through an interposed annular creep plate 36. The swash plate 35 has a hub 37 which turns in bearing bushing 38 mounted in a ring 39. The ring 39 is confined in a seat formed for it in body 6 and sustains the swash plate 35 against axial thrust by means of a creep ring 41.

A radial port 42 leads through the swash plate 35 from counterbore 34. It acts to draw oil through passage 16, chamber 15, and counterbore 34 by centrifugal action, and keep the cam mechanism and plunger ends submerged in oil. The assembly generally indicated at 43 is a shaft seal (for which per se no novelty is here claimed). The function of the seal is merely to prevent oil from leaking out around the shaft. The part 44 is merely the conventional splined driving head for shaft 33.

Except for the guide block 14, chamber 15 and relief valve 25, the pump, as so far described resembles that described and claimed in my Patent No. 2,381,056, dated August 7, 1945.

Pressed into the central aperture of the annular cylinder block 13 is a bushing 45 which forms the cylinder of the pressure control motor. At its left end it is bored to fit stem 46. At its right hand end it is concentrically bored to fit the slightly larger piston sleeve 47. These are lapped fits.

The piston sleeve 47 fits freely on a reduced portion of stem 46 on which it is retained by nut 48, and to which it is sealed by a ring gasket 49 confined in a telescoping annular pocket, as shown. In this way the piston sleeve may have slight lateral motion to accommodate itself to possible eccentricity between the bore and counterbore in cylinder bushing 45.

At midlength the bore of cylinder bushing 45 is relieved or enlarged, and to this enlarged portion a port 51 leads from an encircling groove. To this groove a port 52 (shown in dotted lines in Fig. 1) leads from discharge channel 19.

Stem 46 and its piston 47 are spring biased to the left. Since the effective area of the piston is merely the annular area of the shoulder offered by the difference in diameter between sleeve 47 and stem 46, the springs need not be heavy. It is, however, desirable that the springs be long to permit relatively long travel of stem 46 without marked increase in the spring stress, a condition imposed by the desire to control within a narrow fluid pressure range.

To secure long springs in limited length, two telescopically arranged tandem springs are used. A cuplike flanged spring seat 53 fits over nut 48 and sustains the left end of coil compression spring 54. A cup-shaped flanged spring seat 55 fits over the left end of coil compression spring 56 and sustains the right end of spring 54. A bolt 57 limits separation of the spring seats 53 and 55. The right end of spring 56 is

sustained by adjustable spring seat 58 guided in fitting 59 which is screwed into cap 7 and sealed with a gasket as shown. Seat 58 is adjustable by turning thrust screw 61. Leakage around the screw is prevented by ring gasket 62 and the adjustment is locked by acorn nut 63.

Stem 46 carries a plate 64 which has two functions. When stem 46 is at its leftmost position (assumed when the discharge line is ruptured), it seals at 65 on block 14 and by closing off the counterbored end of shaft 33 traps a charge of oil around the swash plate and plunger ends. This is an ancillary function.

The main function of plate 64 is to adjust the position of spill-back valves 66, one for each plunger 29.

The valves are sleeves through each of which a corresponding plunger works. Each valve is received in a notch in the periphery of the plate 64 and has flanges 67 which straddle the plate. Each valve controls a groove 68 in the periphery of the plunger. To this groove an axial passage 69 and cross-bores 71 lead from the interior of cylinder 22.

When the valves 65 are at the extreme lefthand position shown in Fig. 1 they blank grooves 68 just before the end of the related plunger overtravels groove 26 in its cylinder. These events become simultaneous when normal discharge pressure is approached. As discharge pressure rises through the control range (between normal minimum and maximum, a spread of say 200 pounds per square inch) the valves are moved further and further to the right until at the maximum they reach the positions indicated in Fig. 4 in which the spill-back ports 68 are open throughout the working stroke. The relief valve 25 is set to open just before the maximum discharge pressure is reached.

In the pump as shown and above described, the spill-back occurs during the initial portion of the discharge stroke and this is considered preferable because the spill-back flow starts as cylinder pressure develops.

It is possible however to relocate the grooves 67, and position the valves so that their right-hand faces instead of their lefthand faces perform the control function and the spill-back occurs in the terminal portion of the discharge stroke. In such case the valves are at the right in full capacity setting, blank the spill-back ports in the initial part of the stroke and are overtraveled in the latter part, and hence must be moved to the left to reduce pump capacity. This entails a reversal of the direction of action of the pressure responsive motor and its springs.

It is not deemed necessary to illustrate this alternative arrangement of the same functional parts, a mere reversal of arrangement without significant change of function being all that is involved. Such an arrangement is within the ambit of at least the broader claims.

Other departures from the specific arrangement illustrated will suggest themselves to persons skilled in the art.

What is claimed is:

1. In a pump of the type in which a plurality of cylinders are arranged in circular series with their cylinder axes parallel with the axis of the drive shaft, the combination of a cylinder block having a circular series of cylinder bores; a guide block having a similar series of guide ways, each aligned with a corresponding cylinder bore, said blocks being so formed that the two when assembled enclose an intervening chamber to which

an intake passage leads through one of the blocks; means engaging said blocks to maintain alignment of the guide ways and bores; a divided housing formed to enclose and confine said blocks in assembled relation; a shaft bearing centered in the guide block; thrust and radial shaft bearings supported in the housing, and axially aligned with the bearing in the guide block; a rotary drive shaft mounted to turn in said bearings; a cam carried by said shaft; a plurality of plungers, each extending through a guide in the guide block across said chamber and into a corresponding cylinder bore, said plungers being arranged to be reciprocated by said cam, and each plunger having a spill-back port leading from the corresponding cylinder bore to a point on the plunger within said chamber; spill-back valves, one encircling each plunger within said chamber and each controlling flow through its spill-back port; a pressure motor mounted at the center of the cylinder block, subject to discharge pressure developed by said pump and arranged to shift said spill-back valves in unison; yielding loading means for said motor; and valve means controlling inlet and discharge to and from each cylinder bore.

2. The combination defined in claim 1 in which the housing affords a cam-enclosing space between the bearing in the guide block and the thrust and radial bearings, in which space the cam is located, and the shaft and guide block isolate said cam enclosing space from said chamber except for a passage which leads from the chamber axially through the shaft and thence

6 approximately radially through the cam into said cam-enclosing space.

3. The combination defined in claim 1 in which the housing affords a cam-enclosing space between the bearing in the guide block and the thrust and radial bearings, in which space the cam is located, and the shaft and guide block isolate said cam-enclosing space from said chamber except for a passage which leads from the chamber axially through the shaft and thence approximately radially through the cam into said cam-enclosing space, and the connection between the motor and the spill-back valves includes a part which obstructs said passage through the shaft when the spill-back valves are set in one of their two extreme positions.

4. The combination defined in claim 1 in which the divided housing comprises a body and a cap, the body enclosing the cam mechanism and lateral portions of the guide block and cylinder block, and the cap overlying and engaging the cylinder block; and the yielding loading means is sustained by said cap.
